UNITED STATES PATENT OFFICE.

HARRY J. COLE, OF BENNINGTON, VERMONT.

DESIGN FOR AN EXHIBITING DEVICE.

49,205.

Specification for Design.

Patented June 20, 1916.

Application filed April 20, 1916. Serial No. 92,556. Term of patent 3½ years.

To all whom it may concern:

Be it known that I, HARRY J. COLE, a citizen of the United States, residing at Bennington, in the county of Bennington and State of Vermont, have invented a new, original, and ornamental Design for an Exhibiting Device, of which the following is a specification, reference being had to the

accompanying drawing, forming part thereof, in which a perspective view of an exhibiting device embodying this design is shown.

I claim:

The original design for an exhibiting device, as shown.

HARRY J. COLE.

Copies of this patent may be obtained for five cents each, by addressing the "Commissioner of Patents, Washington, D. C."

It is hereby certified that in Design Letters Patent No. 49,205, granted June 20, 1916, upon the application of Harry J. Cole, of Bennington, Vermont, for a design for "An Exhibiting Device," an error appears in the printed specification requiring correction as follows: In the claim for the word "original" read *ornamental*; and that the said Letters Patent should be read with this correction therein that the same may conform to the record of the case in the Patent Office.

Signed and sealed this 25th day of July, A. D., 1916.

[SEAL.]

F. W. H. CLAY,

Acting Commissioner of Patents.
